AUTOMATIC FIREARM

Application filed June 18, 1929, Serial No. 371,260, and in Germany November 12, 1928.

The invention relates to apparatus in automatic firearms in which the breech mechanism moves axially with the barrel and in which a rearward acceleration is imparted to the breech piece after it has been unlocked from the barrel. The new arrangement is characterized by the efficient impulse imparted to the breech mechanism and by a simple construction adapted to the external form of the breech mechanism, in which manufacture thereof is facilitated by the casing of the weapon forming a cylindrical surface of revolution.

According to the invention, the acceleration relative to the barrel is imparted to the unlocked breech piece by one or more members rotatable about the bore of the barrel, by the parts of the weapon which are moved on firing, so that their wedge-shaped operating surfaces surrounding the axis of the cylinder are inserted between co-operating members of the barrel or of the breech sleeve connected thereto, on the one hand, and the breech piece, on the other hand, and separate the latter forcibly from the barrel.

The accompanying drawing represents an example of a breech apparatus according to the invention applied to an automatic firearm with sliding barrel. The three constructions show in perspective the apparatus partly in section respectively with the breech locked and in two intermediate positions during the recoil of the barrel after firing.

a is the casing of the weapon formed as a hollow cylinder. The breech sleeve b coupled with the barrel, which is not shown, is mounted in the casing a so as to be displaceable but not rotatable. On the rear end of the breech sleeve b, which is provided with a screw-thread b₁, a ring c is screwed which is rotated in the wall of the casing by a lug c₁ secured to and engaging in guides a₂, a₃, when the two parts are relatively displaced in the longitudinal direction. The breech piece d is longitudinally displaceable in the breech sleeve b and projects out of the ring c. The breech piece is guided rectilinearly in the casing slot a₁ and cannot, therefore, rotate in the casing. It is driven forward in known manner by a mainspring which at the same

time acts as the means for moving the barrel forward. The breech piece d has segmental collars d₁ which engage between similar collars c₂ on the ring c and lock these members together. The ring c terminates at the rear in two oppositely disposed lobes c₃, c₄, a similarly directed wedge shaped surface c₅ or c₆ of which co-operate with surfaces d₂, d₃ on the breech piece d. The surfaces c₅, c₆, the collars c₂ of the ring c, the co-operating surfaces d₂, d₃ and the collars d₁ of the breech piece d are so relatively arranged, that the surfaces c₅, c₆ of the ring c only come into engagement with the co-operating surfaces d₂, d₃ of the breech piece when the collars c₂ are out of engagement with the collars d₁.

A spring loaded locking lever e is pivoted in a longitudinal groove of the breech sleeve b and at its rear end projects over an annular extension c₇ terminating the ring c. The member c₇ has at one part a recess c₈ in which the locking lever e can engage. The object of the locking lever e is, at certain positions of the breech piece, to lock the ring c against rotation relatively to the breech sleeve b and consequently against the breech piece d. The lever e is lifted from the recess c₈, in order to allow the ring c to rotate, by a nose e₁ of the lever e cooperating with the breech piece d.

In the description of the method of operation of the breech apparatus, it is assumed that the parts are originally in the position shown in Fig. 1. The breech piece d and the breech sleeve b are in their forward end position in the casing a and are locked together by means of the ring c. After firing, these parts return at first together through a certain distance in the locked condition. The ring c is at first guided in a straight line, the lugs c₁ sliding in the groove a₂, a₃, which, for a short distance a₂, is parallel to the bore of the barrel. At the moment in which the lugs have reached the end of the straight guide a₂ the shot has left the barrel and the pressure of the gas in the barrel is reduced to atmospheric pressure. On the continued recoil of the ring c its lugs traverse the helical portion a₃ of the groove and the ring c is rotated relatively to the breech sleeve b which is further guided in a straight line and the breech piece d; its

locking collars c_2 consequently come out of engagement with the collars d_1 of the breech piece d .

At the end of the unlocking movement, as shown in Fig. 2, the locking lever e engaging over the outer surface of the annular extension c_7 lies over but does not enter the recess c_8 , because its nose e_1 rests on the surface of the breech piece d .

10 Simultaneously with the complete unlocking of the breech piece d from the ring c , the wedge shaped surfaces c_5, c_6 of the latter come into contact with the surfaces d_2, d_3 of the breech piece, while, up to this time, during 15 the unlocking rotation, the distance between these surfaces gradually decreasing. On the continued recoil of the system consisting of the breech sleeve b , ring c and breech piece d , the ring c is further rotated by the inclined 20 guides a_3 and thereby effects the separation of the breech piece from the breech sleeve and its accelerated recoil, the angular rotation of the surfaces c_5, c_6 of the ring c after engaging with the inclined parts of the surfaces 25 d_2, d_3 impels the rectilinearly guided breech piece d rearward.

During the relative movement of the breech piece and sleeve b , a longitudinal groove d_4 of the breech piece, lying radially under the 30 lever e , passes below the nose e_1 of the lever and the lever is moved by spring pressure radially inwards, so that its rear end enters into the recess c_8 .

In the position shown in Fig. 3, the breech 35 sleeve of the barrel and the ring c have attained their end rear position in the casing a of the weapon. The breech piece d has, as above-mentioned, been separated therefrom and continues its accelerated recoil. Its 40 kinetic energy is, as usual, utilized for ejecting the fired cartridge shell. The breech piece is brought to rest by a stop provided in the casing of the weapon and is now again driven forward by the mainspring and effects 45 the feeding of the next cartridge into the barrel.

After reaching their rear end position in the casing of the weapon and the previously described separation from the breech piece, the breech sleeve b , the barrel and the ring c could be again displaced forward independently of the breech piece d , for example, on firing with considerable angular depression. During 55 this forward movement, the ring c is rotated backwards by the inclined guides a_3 in the casing in the direction to again lock the breech piece. The locking lever e which has entered the recess c_8 of the ring limits the backward rotation of the ring c and consequently the 60 further forward movement of the barrel and breech sleeve, so that the collars c_2 of the ring c cannot engage with the collars d_1 of the breech piece or that the breech piece d , which is still in the rear position, runs back 65 into its front end position in the ring c and the

breech sleeve b . Only when the breech piece d , driven forward by the mainspring, has moved so far forward in the ring c , that all the collars d_1 lie between the collars c_2 , is the locking lever e raised from the recess c_8 at the 70 circumference of the extension c_7 by the contact of the end of the groove d_4 of the breech piece with the nose e_1 of the lever e . The ring c is again rotatable relatively to the breech sleeve b and the latter is taken with it 75 by the forward moving breech piece d in the casing a into its front end position. Ring c is thereby further rotated and the breech sleeve b and the breech piece d are again locked together.

Since the locking and unlocking and also the accelerated movement of the breech piece simply depend on a relative rotation of the locking and unlocking members d_1, d_2, d_3 and the co-operating members c_2, c_5, c_6 , in a modified construction the locking collars c_2 and the unlocking members c_5, c_6 might be rigidly connected with the barrel and this could be rotationally controlled relatively to the breech piece d . Or the rectilinearly guided breech piece could itself carry the locking and unlocking ring rotatable relatively to the also rectilinearly guided barrel, in the same manner as the above described ring c . The new breech unlocking devices can obviously 90 be employed with firearms having fixed barrel.

I claim:

1. An automatic firearm, comprising a casing having guides therein; a ring in the casing having lobes thereon and lugs which project into the guides in the casing, said ring also having collars therein and a screw-threaded portion; a breech sleeve displaceably mounted in the casing and having a screwthreaded portion cooperating with the screwthreaded portion of the ring; and a breech piece longitudinally displaceable in the breech sleeve and having surfaces cooperating with the lobes of the ring, said breech piece having collars thereon cooperating with the collars in the ring. 100

2. An automatic firearm, comprising a casing having guides therein; a ring in the casing having lobes thereon and lugs which project into the guides in the casing, said ring also having collars therein and a screw-threaded portion; a breech sleeve displaceably mounted in the casing and having a screwthreaded portion cooperating with the screwthreaded portion of the ring; a breech piece longitudinally displaceable in the breech sleeve and having surfaces cooperating with the lobes of the ring, said breech piece having collars thereon cooperating with the collars in the ring; a locking lever pivotally mounted in the breech piece; and an annular extension at the end of the ring into which the locking lever projects. 115

3. An automatic firearm, comprising a cas- 120

ing having guides and a slot therein; a ring in the casing having lobes thereon and lugs which project into the guides in the casing, said ring also having collars therein and a screwthreaded portion and unlocking surfaces on the lobes; a breech sleeve displaceably mounted in the casing and having a screwthreaded portion cooperating with the screwthreaded portion of the ring; and a breech piece longitudinally displaceable in the breech sleeve and having surfaces cooperating with the unlocking surfaces of the lobes of the ring, said breech piece having a bolt projecting through the slot in the casing and collars thereon cooperating with the collars in the ring.

4. An automatic firearm, comprising a casing having guides and a slot therein; a ring in the casing having lobes thereon and lugs which project into the guides in the casing, said ring also having collars therein and a screwthreaded portion and unlocking surfaces on the lobes; a breech sleeve displaceably mounted in the casing and having a screwthreaded portion cooperating with the screwthreaded portion of the ring; a breech piece longitudinally displaceable in the breech sleeve and having surfaces cooperating with the unlocking surfaces of the lobes of the ring, said breech piece having a bolt projecting through the slot in the casing and collars thereon cooperating with the collars in the ring; a locking lever pivotally mounted in the breech piece; and an annular extension at the end of the ring into which the locking lever projects.

5. An automatic firearm, comprising a barrel; a breech mechanism adapted to move axially with the barrel and when unlocked from the barrel moves relatively rearward; and releasing member having wedge-shaped surfaces rotatable about the bore of the barrel, the acceleration relatively to the barrel being imparted to the breech piece by said wedge-shaped surfaces.

In testimony whereof I have affixed my signature.
